Primary Examiner — Kendra Leslie Hamilton(74) *Attorney, Agent, or Firm* — Young Basile Hanlon & MacFarlane, P.C.(57) **CLAIM**

The ornamental design for a base for fresh food feeder, as shown and described.

DESCRIPTION

FIG. 1 is a top, right perspective view of a base for fresh food feeder showing my new design;

FIG. 2 is a top plan view thereof.

FIG. 3 is a left elevation view thereof.

FIG. 4 is a front elevation view thereof.

FIG. 5 is a right elevation view thereof.

FIG. 6 is a rear elevation view thereof.

FIG. 7 is a bottom plan view thereof; and,

FIG. 8 is a bottom, rear perspective view thereof.

The broken lines in the drawings illustrate unclaimed environmental structure of the base for fresh food feeder and form no part of the claimed design.

1 Claim, 2 Drawing Sheets(56)
